DESIGN FOR A STAPLING DEVICE

Lou Obstfeld, Brooklyn, N. Y., assignor to himself and Abraham I. Obstfeld, New York, N. Y., jointly

Application November 30, 1939, Serial No. 88,871

Term of patent 14 years

To all whom it may concern:

Be it known that I, Lou Obstfeld, a citizen of the United States, residing at Brooklyn, in the county of Kings and State of New York, have invented a new, original, and ornamental Design for a Stapling Device, of which the following is a specification, reference being had to the accompanying drawing, forming part thereof.

The figure is a perspective view of a stapling machine showing my new design, the opposite side presenting substantially the same appearance as the side shown and the hand-rest being of a contrasting color to the other parts of the article.

I claim:

The ornamental design for a stapling device, as shown and described.

LOU OBSTFELD.
